CONTINUOUS ELECTRICAL OUTLET

Winston S. Perkins, Stratford, Conn.

Application July 7, 1948, Serial No. 37,421

9 Claims. (Cl. 173—334.1)

1

This invention relates to new and useful improvements in electrical wiring devices and has particular relation to a convenience outlet device.

An object of the invention is to provide a convenience outlet structure of an elongated configuration and into which a plug cap or other wiring device equipped with prongs may be plugged at any place along the length of such device.

Another object is to provide a device having the characteristics indicated and also including a cover means for the device to prevent accidental injury to anyone coming in contact with the device and to give the device a complete appearance and close it against the entrance of dust, dirt and the like.

A further object is to provide an element of safety whereby the danger of casual or unexpected contact with the conductors of the element will be avoided.

Yet a further object is to provide in connection with an elongated or continuous outlet device an improved means for the mounting of the device whereby the latter may be mounted on the upper edge of a baseboard or in any other convenient location and is properly, yet removably, supported in position.

A still further object is to provide in a continuous outlet device improved corner connector and also an improved connector for use in the connecting of leads with the wiring device as from any or the usual metal outlet box.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is an isometric view showing a corner of a room with the present continuous outlet mounted on the baseboard of such room;

Fig. 2 is a top plan view on a larger scale showing my improved connector connecting the continuous outlet device into a house wiring circuit;

Fig. 3 is a front elevational view of the construction of Fig. 2;

Fig. 4 is a transverse sectional view taken along the line 4—4 of Fig. 3 with a cover in section thereover;

2

Fig. 5 is a longitudinal sectional view taken along the line 5—5 of Fig. 3;

Fig. 6 is a vertical or transverse sectional view taken along the plane of the line 6—6 of Fig. 7;

Fig. 7 is a front elevational view on a larger scale than Fig. 1 and showing a covering for the present continuous outlet;

Fig. 8 is a vertical sectional view showing a plug cap mounted on the present outlet, the view being taken along the line 8—8 of Fig. 9;

Fig. 9 is a front elevational view on a larger scale than Fig. 1 and showing the mounting of a plug cap in the present continuous outlet and between adjacent end portions of a cover;

Fig. 10 is a top plan view on the scale of Fig. 2 showing the corner connector of the present continuous outlet;

Fig. 11 is a view partly in front elevation and partly in transverse section, the view being taken along the plane of the line 11—11 of Fig. 10;

Fig. 12 is an isometric view of a conductor strip employed in a corner connector of the present continuous outlet structure; and

Fig. 13 is a similar view of a conductor strip employed in the connector through the medium of which the present continuous outlet is connected in the house wiring system.

Referring in detail to the drawings, at 10 is indicated, in broken lines, a corner portion of a room including walls 11 and 12 and a baseboard 13. For the present purpose, my improved continuous outlet construction is shown as mounted on the upper edge of the baseboard 13, although it will be understood that the construction may be used in any desired or convenient location.

My improved continuous outlet is shown in Fig. 1 in a general assembly and there such outlet includes an elongated body 14, the details of construction of which will be given, a spring metal

mounting structure or strip generally designated 15, a cover structure which is provided in the desired lengths and which is disclosed in three sections in Fig. 1, each such section being generally designated 16, a connector 17 for connection of

the continuous molding with the house wiring circuit, and a corner connector 18 for the continuous body 14. Also, in that figure, a plug cap is generally designated 19. This plug cap 19 is shown as of a general configuration somewhat

similar to that of the cover structure 16 and as located between adjacent ends of a pair of cover sections specifically designated 20 and 21.

The continuous outlet 14 is best extruded with a pair of spaced elongated conductors 22 and 23 therein. The outlet 14 comprises an elongated

body 24 of insulating material and it has been illustrated as being formed by extrusion processes. This body 24 is shown as approximately square in transverse section (see especially Figs. 6 and 7) and in its upper wall, toward its rear edge, is provided with a notch 25 and in its lower side, toward its forward edge, with a notch or recess 26. It will be understood that the conductors 22 and 23 are co-extensive with any particular section of the body 24 and they are located well within the body and access is to be had to them through entrance slots 27 and 28 opening through the front or outer edge of the body and in their inner ends terminating entering transversely circular passages 29 and 30 located at the upper and lower sides, respectively of the conductors 22 and 23.

It is noted that the entrance slots 27 and 28 are located somewhat above and below the upper and lower surfaces of the conductors 22 and 23 so that there is a slight drop-off from the inner ends of said entrances to said conductors. The purpose of this is to prevent casual contact with the conductors should a child push a hairpin or the like through the entrance slots. Intermediate the ends of the entrance slots and in their respective upper and lower sides, such slots are shown as provided with slight recesses 31 and 32, respectively, the purpose of which will appear.

The metal mounting strip 15 is employed for the proper locating and mounting of the continuous outlet molding or device 14. Such mounting strip 15 is, of course, elongated and transversely it is somewhat L-shaped in that it includes a back portion 33 and a bottom or lateral portion 34. In addition, the upper edge of the back 33 is bent forwardly providing a narrow forwardly projecting extension 35 approximately parallel with the lower wall 34 and then this extension is bent inwardly at right angles providing a lip 36. Additionally, the forward or free end portion of the bottom wall 34 is bent to provide a transversely curved spring lip 37.

The strip 15 is mounted in any suitable manner but is shown as secured to the baseboard 13 by screws 38 passing through the bottom wall 34 of the strip and preferably having their heads countersunk in such wall and then threaded into the baseboard. Additionally, screws 39 pass through the vertical or rear wall 33 of the strip and preferably have their heads countersunk in such wall and then such screws are shown as threaded into the wall structure 11 of the room. In connection with the mounting of the strip 15, it is to be understood that the screws 38 and 39 may both be used as illustrated or if the mounting only permits of the use of screws through one wall of the strip, that will generally be found sufficient.

Additionally, it is preferred that the screw holes in the strip walls be spaced but short distances apart since then when only a short length of the strip is used, any particular connection, even a short length, will have sufficient holes for the passage of the necessary securing screws. In this connection it will be understood that the strip may be provided in lengths and then sawed or otherwise cut to the desired lengths on the job.

When the strip is in place, the body 14 is mounted by arranging it at a slight angle and placing its lower rear corner on the wall 34 of the strip and with its upper rear corner as much as possible in the rear of the lip 36 of the spring metal strip. Then the body is simply rocked downwardly to locate it in the inner or rear por-

tion of the recess 26 provided in the bottom forward edge of the body 14. To remove the body 14, it is simply rocked in the opposite direction until it is released and then it is lifted out. It is noted that the rear corners of the body are constructed on arcs to permit of the described rocking movement for the mounting and removal of the body.

With the construction described, it will be understood that for any particular installation, the proper length of strip 15 is provided and such length may be cut from a strip of indefinite length. Similarly, the proper length of the outlet body 14 is provided. However, simply mounting 15 of the strip and the snapping of a body section into a section of the strip does not provide the necessary wiring connections to the conductors 23 and 22. This connection is provided through the employment of a connector device such as that generally designated 17 in the drawings.

Connector 17 comprises a body of insulating material including a rear wall 40, bottom wall 41 and end walls 42 and 43. There is no front wall in the connector 17 and the same is not herein considered as including a top wall, although it does include a very slight forwardly projecting upper ledge 44 shown as of a size or width substantially equal to the thickness of the lip 36 of the strip 15 and terminating about flush with the bottom of a notch or recess 45 provided in the upper edges of the end walls 42 and 43 and arranged to align with the notch 25 of a section of the body 14 when the connector 17 and such body section are mounted by the strips 15.

When using one of the connectors 17, it is preferred that the same be located over any or the usual metal wall outlet box and such box is suggested at 46 by dotted or broken lines in certain figures of the drawings. These boxes 46 are customarily provided with mounting ears 47 and 48 extending from their respective ends and for my purpose, I pass anchoring screws 49 through adjacent end portions of the walls 33 of a pair of strips 15 and thread such screws into the ears 47 and 48. In this way, the outlet box 46 is mounted.

To permit of adjustments of the outlet box or of the metal strips 15 employed, the latter in their adjacent end portions are provided with elongated openings 50 through which the screws 49 pass. Here it is also noted that while end portions of the strips 15 extend over or across the ends of the box 46, the adjacent ends of the strips are somewhat spaced leaving an opening 51 which aligns with an opening 52 in the rear wall 40 of the connector 17. Through these openings, leads 53 and 54 are carried.

These leads are connected, respectively, with lower and upper conductors 55 and 56 mounted in the connector 17 and preferably anchored to the rear wall of the latter as by screws, rivets or the like 57. Binding posts 58 and 59 secure leads 53 and 54 to the respective conductors 55 and 56. Each of these conductors is generally U-shaped and one of them is shown alone in Fig. 13. Thus, each conductor 55 or 56 includes a strap-like back portion 60 having the tapped eyelet 61 to receive the binding post and having an opening 62 for the passage of the anchoring screw 57. Additionally, each of the mentioned conductors includes forwardly projecting ends 63 and 64 having openings 65 and 66 towards their free ends for the passage of screws, as will appear.

In the connector 17 the conductors 55 and 56

are mounted toward the upper and lower edges of the insulating body so as to leave clear the opening 52 through the rear wall of such body and also to amply space the conductors from one another to avoid any chance of short circuit. The strap-like rear portion 60 of the conductor 56 lies just under the slight ledge 44 on the forward edge of the upper portion of the wall 40 of the insulating body of the connector 17 so as to be separated by such portion 60 from any possibility of contact with the lip 36 of the strip 15.

Self-tapping screws 67 pass through the openings 65 and 66 of the ends of the conductors 55 and 56 and through the adjacent portions of the end walls 42 and 43 of the connector body. While these screws have a purpose of establishing electrical connections between the conductors 55 and 56 and the conductors 23 and 22 in the bodies 14, such screws also serve to assist in mounting the conductors 55 and 56 in the insulating bodies of the connectors 17. The screws 67 are passed through the ends 63 and 64 and the walls 42 and 43 from the inner sides of the insulating body of which said walls constitute parts. Thus, the heads of the screws are located within said body. However, since the body is open at its front and top sides, access is had for the anchoring of the leads 53 and 54 to the binding posts 58 and 59 and to the heads of the screws 67 for the turning of the latter.

The conductor strips 55 and 56 are located approximately in the same vertical relation as the conductors 23 and 22 of the body 14 and the end walls 42 and 43 of the insulating body of the connector 17 are approximately the size and shape of an end of the body 14. Therefore, after a pair of the sections of strip 15 has been used to mount a wall box 46 and a connector 17 has been mounted on the adjacent end portions of said strips in spanning relation with their spaced ends, the necessary securing of the leads 53 and 54 to the strips 56 and 55 may be made.

Then a pair of sections of the desired length of the elongated body 14 are snapped into place in the strips 15 at each end of the insulating body of the connector 17. The adjacent ends of the body or section 14 are pushed against the outer sides of the end walls 42 and 43 of the connector 17. This will bring the openings 65 and 66 of the conductors 55 and 56 into alignment with the transversely circular passages 30 and 29 at the outer sides of the conductor strips 23 and 22. These transversely circular passages have a diameter equal to the diameter of the body of a screw 67 to the root of its thread.

Now, these screws 67 are threaded into the end portions of the passages 30 and 29 of the body 14. As this is done, the threads of the screws bite into the conductors 23 and 22 and also into portions of the body 14 about the openings 30 and 29. In this way, a good electrical and mechanical connection is established through the screws between the conductors 55 and 56 of the connector 17 and the conductors 23 and 22 of the body 14. At this time, assuming the leads 53 and 54 to have been connected up, using the binding posts 58 and 59, it will be seen that the conductors 23 and 24 are connected in the house wiring circuit.

The cover sections 16 are provided in pieces of considerable length and it is planned that they would be sawed or otherwise cut to desired lengths on the job. Each such cover section comprises a hollow body or shell-like portion 68, comprising

a lower straight portion 68a and an upper curved or arcuate portion 68b. The arcuate portion constitutes approximately one-quarter of a circle or is of any other contour. On the inner side of the lower straight portion 68a are vertically spaced ledge-like portions or legs 69 which extend for the length of the cover or from end-to-end thereof and preferably are formed integral therewith. The legs 69 are outwardly curved or off-set providing lip portions 70 along their free edges. This construction is as clearly shown in Fig. 6.

After the continuous outlet body 14 is mounted in place it will be understood that its entrance slots 27 and 28 open through its forward edge for its entire length. In fact, these slots are shown as somewhat flared at their entrance ends. Now, a cover section 16 of the proper length may be disposed over the body 14 as suggested best in Figs. 1 and 6. To mount this cover section, its leg portions 69 are inserted into the entrances 27 and 28 and simply pushed in. The lip-like portions 70 at the free ends of said legs snap into the notches 31 and 32 formed in the upper and lower walls, respectively, of the entrances 27 and 28 and thus serve to hold the cover in place.

While the cover is in place, its upper curved portion 68b preferably extends back over the body 14 to engage the wall portion above such body somewhat in the nature of a molding and extends downwardly to cover the recess 26 and preferably laps over the baseboard. Therefore, the cover section 16 completely conceals the elongated body 14 and its mounting and forming a cover over the same prevents the upper edge of such body and mounting from forming a shelf-like structure to collect dust and the like. The cover section gives a completed appearance or a finish to the entire installation.

In a corner, the ends of the cover sections extending to the corner are preferably cut to form a miter joint as suggested by the line 71 of Fig. 1 and the portions of the cover overlapping the corner connector 18 will not be equipped with the legs or ledges 69 so that such legs or ledges will not interfere with or project into such connector 18.

Since the cover comprises the sections 16, and the body structure 14 and its conductors 22 and 23 provide a continuous outlet, it will be understood that a plug cap may be connected into the outlet at any desired place along the length of the latter. Preferably, any outlet employed is of somewhat the construction of the outlet 19 of the drawings and, in addition to a body 72 mounting contact prongs 73, will include an upper arcuate or rearwardly curved portion 74 of the general curvature of the part 68b of a cover. Wherever a plug cap is to be plugged in, the cover will be severed, probably a part removed, to leave a space between the severed ends of the cover of a width to accommodate the plug cap.

Then the prongs 73 of the plug cap are inserted through the entrances 27 and 28 and snap or spring into engagement with the conductors 22 and 23. For this purpose, the upper prong 73 has a depending inner end portion 75 while the lower prong 73 has an upwardly bent or curved inner end portion 76. These end portions will snap over the portions of the insulating body 14 at or toward the forward edges of the conductors 22 and 23 and into engagement with said conductors. The prongs 73 are shown as electrically connected with binding posts 77 to which the

wires of a conductor 78 are anchored, such conductor 78 being any lead cord.

The corner connector 18 is more particularly disclosed in Figs. 10, 11 and 12. Such connector includes a body 79 of insulating material and the latter comprises a pair of integral portions located at right angles to one another and including a bottom wall or base portion 80, upstanding right angularly disposed back or rear wall portions 81 and end walls 82 and 83. These end walls are located at the ends of the right angularly related portions of the body 79 and in planes normal to one another and are of the height of the rear wall portions 81. From the foregoing, it is to be understood that the body 79 is open at its upper side with the exception of a slight forwardly projecting ledge 84 corresponding in purpose with the ledge 44 of the connector 17 previously described and of a width equal to, or substantially equal to the thickness of the depending lip 36 of the extension 35 of the mounting strip 15.

Within the body 79 are mounted a pair of upper and lower conductors 85 and 86 of identical construction and of which the conductor 85 is shown alone in Fig. 12. Each conductor includes right angularly related portions 88 which are fastened against the inner sides of the respective rear or back wall portions 81 of the body 79 and are secured in place as by screws or the like 89, passing through holes 89a.

Additionally, each conductor includes ends 90 and 91 provided with openings 92 and 93. These ends 90 and 91 lie against the inner surfaces of the end walls 82 and 83 of the body 79 and self-tapping screws 94 are passed through such openings. It will be understood that the ends 90 and 91 and the openings 92 and 93 of the respective upper and lower conductors 85 and 86 of a corner fitting bear the same relation to the transversely circular passages 29 and 30 and the conductors 22 and 23 of a body 14 as do the ends 63 and 64 and the holes 66 and 65 of the conductors 56 and 55 of a connector 17.

Thus, after a corner coupling or fitting 18 is secured in place by being fitted to adjacent end portions of a pair of strips 15, the adjacent ends of a pair of the bodies 14 are brought up against the outer sides of the end walls 82 and 83 of such corner coupling. Then the self-tapping screws 94 are passed through the openings 92 and 93 and threaded into the passages 29 and 30 of the respective bodies 14. These screws have body diameters approximately equal to the diameters of the passages 29 and 30 whereby as the screws are threaded home their threads cut or bite into the wall portions of the passages 29 and into the conductors 22 and 23. In this way, the screws are anchored in place and assist in anchoring the conductors 85 and 86 and also establish a good electrical connection between such conductors and the conductors 22 and 23.

From the foregoing it will be seen that my continuous outlet is easily and conveniently installed. Through the use of my corner connectors a neat structure at the corner is provided and there is no change in the appearance of the device as between the corner or any of its other portions. Due to my corner construction, it is not necessary that an outlet 17 be fitted for each wall space as the conductor may be continued around the corner without difficulty. Thus, the only place I need employ the outlet fitting 17 is as between a pair of door openings

or other openings which would definitely interrupt the employment of a single outlet for an entire room.

In constructions heretofore employed, the corner connectors have not been satisfactory and have not been of simple construction and neat appearance. With my present corner connector as well as with my inlet connector 17, the top and front of each connector is open so that a small wrench or the like may be employed for threading home the self-tapping screws 67 of the connector 17 and 94 of the connector 18.

Having thus set forth the nature of my invention, what I claim is:

1. In a continuous outlet structure, an elongated body of insulating material, a pair of spaced conductors within said body and extending longitudinally thereof, a pair of entrance slots opening through the forward edge of said body and extending longitudinally thereof and at their inner ends communicating with the respective conductors, said body having a notch opening laterally into one of said entrance slots intermediate said conductors and the forward edge of the body, a cover for said body comprising a straight portion extending across the forward edge of the body and an arcuate portion extending across the upper edge of the body and comprising approximately one-quarter of a circle, a leg on the inner side of said straight portion of said body and located in one of said entrance slots for the mounting of said cover on said body, and said leg having an offset inner edge located in said notch for the purpose of preventing casual separation of said body and cover.

2. In a continuous outlet structure, a metal mounting strip comprising a pair of angularly related wall portions, a short lateral extension on one of said wall portions and in substantially parallel relation with the other wall portion, a lip on the free edge of said extension and extending in the direction of said other wall portion, said strip having openings through said wall portions for the passage of securing screws, an elongated body of insulating material, a pair of spaced conductors within and extending longitudinally of said body, said body having entrance slots extending longitudinally thereof and opening through one edge and providing for communication with the respective conductors through said edge, said body adapted to be fitted into said strip and having a pair of angularly related walls to engage against the inner surfaces of the angularly related wall portions of said strip, said body having a notch in one edge adapted to receive said lip on said extension of said strip, a cover of insulating material, said cover comprising a straight portion extending across said edge of said body, an upper arcuate portion comprising approximately one-quarter of a circle and extending across the upper edge of said body, and a leg on the inner side of said straight portion of the cover and located in one of said entrance slots for mounting the cover on said body.

3. In a continuous outlet structure, a pair of elongated bodies of insulating material, said bodies each having a spaced pair of transversely circular passages extending longitudinally thereof, a pair of spaced conductors within each said body and extending longitudinally thereof in substantially tangential relation to and with portions exposed through walls of said respective passages, a pair of entrance slots extending longi-

tudinally of each said body and opening through one side thereof and in their inner portions communicating with the respective conductors, a connector between said bodies and comprising a body of insulating material including angularly related walls and end walls, said elongated bodies at their adjacent ends abutting said end walls of said connector, a pair of conductor strips in said connector and spaced from one another and including end portions against the inner surfaces of the end walls of said connectors, and screws passing through said end portions and said end walls and into the adjacent portions of said transversely circular passages and having their threads biting into the walls of said passages and the exposed portions of the respective conductors of the respective bodies whereby said connector through its conductors electrically connects the conductors of one of said elongated bodies with the respective conductors of the other elongated body.

4. In a continuous outlet structure, a pair of elongated bodies of insulating material, said bodies each having a spaced pair of transversely circular passages extending longitudinally thereof, a pair of spaced conductors within each said body and extending longitudinally thereof in substantially tangential relation to and with portions exposed through walls of said respective passages, a pair of entrance slots extending longitudinally of each said body and opening through one side thereof and in their inner portions communicating with the respective conductors, a connector between said bodies and comprising a body of insulating material including angularly related walls and end walls, said elongated bodies at their adjacent ends abutting said end walls of said connector, a pair of conductor strips in said connector and spaced from one another and including end portions against the inner surfaces of the end walls of said connector, screws passing through said ends and said end walls and into the adjacent portions of said transversely circular passages and having their threads biting into walls of said passages and the exposed portions of the respective conductors of the respective bodies whereby said connector through its conductors electrically connects the conductors of one of said elongated bodies with the respective conductors of the other elongated body, said connector having an opening through one wall thereof for the entrance of leads, and binding posts on the respective conductors of the connector for the securing of leads thereto.

5. In a continuous outlet, a pair of metal mounting strips each including bottom and rear substantially right angularly related walls, a lateral extension on the upper edge of said rear wall and a lip on the free edge of said extension and extending towards said bottom wall, said strips arranged with their adjacent ends in slightly spaced relation, a connector including a body of insulating material open at its top and forward sides and including substantially right angularly related rear and bottom walls, end walls, and a short ledge extending forwardly from its rear wall below the upper edge of the latter, said body arranged in spanning relation with the spaced adjacent ends of said strips and having its bottom wall against the bottom walls of said strips and its rear wall against the rear walls of said strips and with the upper edge of its rear wall under said extensions of said strips, said lips of the extensions of the rear walls of the strips extending over the forward edge of the

rear wall of said insulating body and disposed on said ledge, a pair of conductors in said body and comprising portions against the inner surfaces of the rear wall thereof and ends against the inner surfaces of the end walls thereof, said conductors spaced apart within said body, an opening through the rear wall of said body, leads entering said connector through said opening and between the adjacent ends of said strips, means connecting said leads with the respective conductors, contact means passing through the ends of said conductors and said end walls of said body, elongated bodies of insulating material in said strips beyond the end walls of said body, spaced conductors within and extending longitudinally of each of said bodies, and said contact means beyond the end walls of said body entering said elongated bodies and engaging the respective conductors therein.

6. In a continuous outlet structure, a connector comprising body of insulating material comprising a pair of right angularly related portions, said body in said portions comprising rear and bottom walls and open through its top and front edges, end walls closing the ends of said body at the extremes of said portions, upper and lower conductors in said body against the rear wall thereof, each of said conductors including angularly related body portions against the similarly related portions of said rear wall, ends on said body portions of the conductors and located against the inner surfaces of said end walls of the body, a pair of elongated insulating bodies each having an end disposed against the outer side of an end wall of said connector, said bodies each having a spaced pair of transversely circular passages therein and extending longitudinally thereof, a pair of spaced conductors within each of said bodies and extending longitudinally thereof in substantially tangential relation to and with portions exposed through the walls of the respective passages, a pair of entrance slots extending longitudinally of said body and opening through one side thereof and in their inner portions communicating with the respective conductors, self-tapping screws passing through the ends of the conductors of said connector and the end walls of the insulating bodies thereof, and said passages in said elongated bodies so located with respect to said screws that as said screws are threaded home their threads cut into the walls of said passages and the exposed portions of said conductors whereby said connector serves to establish electrical connection between the conductors in one elongated body and the respective conductors in the other of such elongated body.

7. In a continuous outlet structure, an elongated metal mounting strip comprising first and second angularly related wall portions, a lateral extension on the second of said wall portions and in substantially parallel relation with the first wall portion, a lip on the free edge of said extension and extending in the direction of said first wall portion, said strip having openings through said wall portions for the passage of securing screws, an elongated body of insulating material, a pair of spaced conductors within and extending longitudinally of said body, said body having entrance slots extending longitudinally thereof and opening through one edge and providing for communication with the respective conductors through said edge, said body adapted to be fitted into said strip and having first and second angularly related walls to engage respectively against the inner surfaces of the first and

second angularly related wall portions of said strip, said body having a third angularly related wall angularly related to the second of its angularly related walls, said body having a notch opening through the outer surface of its third angularly related wall and extending longitudinally thereof in the same spaced relation to the second angularly related wall of the body as is said lip to the second angularly related wall portion of said strip, and said extension on the second angularly related wall portion of a width less than one-half the width of the first wall of said strip whereby said body may be held at an angle and its third angularly related wall located under said extension with the notch in said wall receiving said lip and then the body rocked about said lip to carry the first and second angularly related walls of the body against the corresponding walls of said strip.

8. A means for mounting a continuous outlet comprising an elongated metal strip including a pair of substantially right angularly related wall portions, a lateral extension on the longitudinal edge of one of said wall portions and extending therefrom substantially in parallel relation with the other wall portion, a lip on the free longitudinal edge of said lateral extension and extending therefrom in the direction of said other wall portion, said wall portions having openings therethrough for the passage of securing means, a bowed lip on the free edge portion of said other wall portion and bowed in the direction of said extension, an insulating body of a size and shape to be received in said strip with outer surface portions engaging the angularly related walls of the latter, said body having a longitudinally extending notch opening through one surface intermediate the longitudinal edges of said surface and receiving the first mentioned lip, said body having a recess in its surface opposite that having the notch and located laterally outwardly of said notch and receiving said bowed lip, and said extension of a width less than one-half that of the wall with which it is substantially parallel whereby said insulating body may be held at an angle and its notch receiving the first mentioned lip and may then be rocked about said lip into

said strip to bring portions of the body against the angularly related walls of the strip and to engage the recess of the body of the bowed lip of the strip.

- 5 9. A means for mounting a continuous outlet comprising an elongated metal strip including first and second substantially right angularly related wall portions, a lateral extension on the edge of the second of said wall portions and extending therefrom in parallel relation with the first wall portion, a lip on the free edge of said lateral extension and extending therefrom in the direction of said first wall portion, said wall portions having openings therethrough for the passage of securing means, said extension of a width less than one-half that of the first wall portion whereby an insulating body having at least three angularly related sides may be held at an angle and a portion of one of its sides engaged under said lip and said body then rocked about said lip into place in said strip with its other two angularly related sides against the inner surfaces of the angularly related first and second wall portions of said strip, and a lip on and coextensive with the free longitudinal edge of said first wall portion and bowed in the direction of said extension for reception in a recess in a wall of the body.

WINSTON S. PERKINS.
